DRIER FOR YARNS OR CORDS

Martin Castricum, Grosse Pointe, Mich., assignor
to United States Rubber Company, New York,
N. Y., a corporation of New Jersey

Application June 17, 1943, Serial No. 491,158

4 Claims. (Cl. 34—154)

This invention relates to a drier for yarns or cords and more particularly to an extremely simple tube construction for rapidly drying yarns or cords which are being advanced under tension.

The drier of the present invention may be employed in various fields to dry strands under tension before they are wound into a package, but has been developed more particularly for use in connection with the apparatus of the Hansen and Benson U. S. application, Serial No. 491,160, filed June 17, 1943, Method of and apparatus for treating yarn or cord.

In treating yarns or cords in accordance with the application just mentioned, it is important to dry the wet and highly stretched yarns or cords under tension as they are advanced towards the winding or packaging mechanism so that they will be dry by the time they reach the package forming position, and it is important to dry such yarns or cords as rapidly as can be done without scorching them since the speed with which the yarns or cords can be treated upon such apparatus depends upon the speed of the drying operation.

The primary feature of the present invention resides in a long heated tube having a hard smooth outer surface over which yarns or cords to be dried may slide freely in direct contact with the surface of the tube as they travel lengthwise thereof. Direct contact of the yarns or cords with the heated surface of the tube throughout its length is secured by causing such yarns or cords to travel in a long spiral path about the tube so that their tension will hold the spirals in contact with the tube surface.

One important advantage of the present type of drier resides in the construction whereby it is free from operating parts, and another advantage resides in the fact that the tube may be many feet long so that each yarn or cord will travel in direct contact with its hot surface throughout a distance of many feet to dry it rapidly. Another advantage of the present construction resides in the fact that it is relatively easy to maintain the tube at any desired temperature and to control the tension of the yarns or cords during the drying operation.

The above and other features of the present invention will be more fully understood from the following description when read in connection with the accompanying drawing wherein:

Fig. 1 is a side elevation of a drier for yarns or cords, constructed in accordance with the present invention.

Fig. 2 is a similar view on a larger scale with

parts in section and with the central portion of the tube broken away, and;

Fig. 3 is a section taken on the line 3—3 of Fig. 2.

5 The drying tube 10 may vary in diameter from several inches to many inches depending largely upon the number of yarns or cords that are to be advanced simultaneously along its surface and the length of the tube may be ten, twenty or more feet depending upon the speed at which it is desired to dry the yarns or cords. It is apparent that the greater the length of the tube the quicker the yarns or cords traveling lengthwise thereof in contact with its surface can be dried without subjecting them to such high temperatures that they are likely to be charred or otherwise injured by the heat of the tube.

10 The tube 10 is preferably made of metal such as steel having a ground surface which is plated and polished so that the yarns or cords will slide smoothly upon its surface, and so that the surface will not rust or corrode from the moisture on the wet strands.

15 The tube 10 may be heated by various means but is preferably heated by steam, for temperatures above the boiling point, and by hot water for temperatures below the boiling point. In most cases it will be desirable to heat the tube to a temperature well above the boiling point by the use of super-heated steam, and in this case the tube 10 will need to be strongly constructed and capable of confining steam under considerable pressure. The tube 10 may therefore be given the construction illustrated in Fig. 2 wherein it

20 25 30 35 will be seen that the long tube proper 11 has its ends closed with the metal heads 12 and 13 which are fitted within the ends of the tube 11 and welded in place. The tube 10 is shown as provided with the steam inlet pipe 14 threaded centrally through the head 12, and with the outlet pipe 15 leading from the lower wall of the tube 11 adjacent the head 13 and through which steam and water that condenses out of the steam may escape.

40 45 50 In order that water which condenses inside the tube may drain therefrom, it is desirable to support the tube 10 in a slightly inclined position as shown in Fig. 1 so that the outlet pipe 15 will extend downwardly from the lowest portion of the tube. The tube 10 is therefore provided at its opposite ends with the supporting rods 16, the lower ends of which are bent laterally to extend into drill holes formed in the heads 12 and 13 and are preferably welded therein, and the upper ends of these rods are threaded as shown to re-

ceive the turn buckles 17 which cooperate with the rods 18 to suspend the tube 10 at the desired inclination from the overhead structure or supporting frame 19 having the transverse bars 20 to which the rods 18 are secured.

The yarns or cords 21 to be dried may be supplied to the tube 10 in a wet condition from any yarn or cord treating mechanism, not shown, and advanced lengthwise of the tube in the direction indicated by the arrow. These yarns or cords may be advanced under controlled tension by any suitable means.

It is desirable to maintain the yarns or cords in spaced relation to each other throughout the drying operation and to cause them to press firmly against the smooth outer surface of the tube throughout its length. To this end, in the construction shown there is provided at the right-hand end of the tube 10 the yarn or cord guiding disc 22 supported by the stub shaft 23 extending from the head 13 in an axial direction. The disc 22 is secured upon this shaft at the desired distance from the end of the tube by the set screw 24. This disc is provided with a number of yarn guiding apertures 25 disposed concentrically about the axis of the drum 10 as best shown in Fig. 3. A similar disc 22 is provided at the opposite end of the tube 10 and is mounted upon the steam inlet pipe 14.

The arrangement is such that the concentrically disposed apertures 25 serve to hold the yarns or cords 21 in spaced relation to each other as they approach the tube 10 and are delivered thereto, and the desired long spiral movement is imparted to these yarns or cords as they travel along the tube by winding them around the tube, say for one complete revolution as shown, from one guide disc 22 to the other. By this simple construction without moving parts the yarns or cords 21 are maintained in spaced relation to each other and in direction contact with the surface of the tube 10 throughout their travel along the tube, and due to their contact with the hot surface of the tube throughout its length they will be dried rapidly so that upon leaving the discharge end of the tube they will be practically free of moisture.

Having thus described my invention, what I claim and desire to protect by Letters Patent is:

1. A drier comprising a long heated tube having a hard smooth outer surface over which yarns or cords will slide freely, guide means at one end of the tube for guiding yarns or cords to the tube and at the opposite end of the tube for guiding them therefrom so that when the yarns or cords are drawn forward under tension they will contact the outer surface of the tube and travel lengthwise thereof in long spiral paths in drying engagement with the tube.

2. A drier comprising a tube having a hard smooth outer surface over which yarns or cords 15 will slide, means for supplying a heating fluid to the interior of the tube, guide means at one end of the tube for guiding yarns or cords to the tube and at the opposite end of the tube for guiding the yarns or cords therefrom so that when they 20 are drawn forward under tension they will contact the outer surface of the tube and travel lengthwise thereof in long spiral paths in drying engagement with the tube.

3. A drier comprising a heated tube having a 25 hard smooth outer surface over which yarns or cords will slide, guides at the opposite ends of the tube disposed concentrically about the tube axis and adapted to guide a number of spaced yarns or cords to one end of the tube and from its 30 other end so that when they are advanced under tension lengthwise of the tube they will contact its outer surface and travel in long spiral paths in drying engagement with the tube.

4. A drier comprising a metal tube adapted to 35 have a heating medium circulated therethrough, and formed with a smooth outer surface over which yarns or cords will slide, guide means supported by the tube at its ends in concentric relation about the tube axis and adapted to guide a 40 number of spaced yarns or cords to one end of the tube and from its other end so that when they are advanced under tension lengthwise of the tube they will contact its outer surface and travel in long spiral paths in drying engagement with the 45 tube.

MARTIN CASTRICUM.
